ASSIGNORS TO MEAD JOHNSON & CO., OF JERSEY CITY, NEW JERSEY, A CORPO-
RATION OF NEW JERSEY.

METHOD FOR DRYING LIQUIDS.

1,200,116.

Specification of Letters Patent. Patented Oct. 3, 1916.

Application filed March 8, 1915. Serial No. 12,858.

To all whom it may concern:

Be it known that we, EDWARD MEAD JOHNSON and ERNEST J. COLLINGS, citizens of the United States, residing at Jersey City, in Hudson county, in the State of New Jersey, have invented certain new and useful Improvements in Methods for Drying Liquids, of which the following is a specification.

10 This invention relates to methods for drying liquids wherein the liquid is dried while thinly spread upon a surface, and is applicable to all liquids, particularly those containing a solid matter in suspension or solution.

15 An object of the invention is to dry highly adhesive solutions—especially those which are extremely adhesive when heated—by this method.

20 A further object of the invention is to dry mixtures composed of solutions of different degrees of adhesiveness and to regulate the proportions of the different solutions so as to obtain the desired constitution of the 25 dried product.

Our new process of drying consists fundamentally in spreading a film of a solution of comparatively low adhesiveness over the surface upon which the drying is to take 30 place and applying upon this film a film of the more adhesive solution to be dried.

An important application of the process is the drying of syrups. Malt sugar syrup, for example, consists principally of two 35 substances, dextrin and maltose in solution. The maltose is extremely adhesive when heated, while the dextrin is much less so. In former processes it has been customary to dry the malt sugar syrup by spreading a 40 film of the mixture of dextrin and maltose in solution over the heated surface. This results in bringing a part of the heated maltose in contact with the heated surface and its extreme adhesiveness makes it difficult to 45 remove from the heated surface after drying. It is practically impossible to remove the dried film when the ratio of the maltose to the dextrin in the solution is greater than 55:45. According to our new process, a so-

50 lution containing either pure dextrin or a high percentage of dextrin and a solution containing a high percentage of maltose are spread upon the heated surface separately and successively. A film of the high dex-

trin solution is first applied and over this a 55 film of the high maltose solution. The film high in dextrin prevents the maltose from coming in contact with the heated surface and in consequence the two films may easily be scraped off when dried. 60

In order that our invention may be clearly understood, we shall proceed to describe the particular adaptation of it which is illustrated in the accompanying drawing. It should be clearly understood, however, that 65 our invention is by no means limited to the particular embodiment illustrated and described.

In the accompanying drawing, Figure 1 is a cross-sectional elevation of a device embodying our invention. Fig. 2 is a fragmentary section of a modified form of the device. 70

In the form illustrated the drying apparatus is inclosed in an air-tight casing 1, to 75 which is connected an exhaust pipe 13. This makes it possible to conduct the drying in a vacuum. The use of a vacuum is, however, not essential to our invention and whether or not it is to be used in connection with our 80 invention may be determined by practical considerations as to the cost and rapidity of drying required and particularly by the nature of the solution to be dried.

The drying roller 2 is supported upon a 85 horizontal axle, one end of which is hollow to permit the introduction of steam into the interior of the roller. Any convenient form of mechanism, not shown, is provided to rotate the roller in an anti-clockwise direction. 90 This mechanism is such that the speed of rotation may be varied. Below the roller 2 are the rollers 3 and 4. These rollers are supported upon horizontal axles and are preferably capable of being steam heated 95 like roller 2. A very small clearance is allowed between these rollers and roller 2, that between roller 3 and roller 2 being equal to the thickness of the film of the liquid to be dried, and that between roller 4 and roller 100 2 being equal to the thickness of two films of solution. Rollers 3 and 4 are provided with mechanism (not shown) by which they can be rotated in the clockwise direction. Surrounding the lower portions of the rollers 3 and 4 are the troughs 5 and 6, in which are placed the solutions to be dried. Inlet 105 pipes 7 and 8 are provided to admit the so-

lutions to the troughs 5 and 6, respectively. The troughs are also provided with outlet pipes 9 and 10, which are used when the troughs are washed out. A knife 11 is provided to scrape the dried films from the roller 2. From the knife the dried product descends into the receptacle 12.

The operation of the apparatus illustrated in Fig. 1 is as follows:—Steam is admitted to the roller 2, and preferably to rollers 3 and 4 also, to heat them. The solutions to be dried are introduced into the troughs 5 and 6 through pipes 7 and 8, the more adhesive solution being placed in trough 6. If, for example, the solution to be dried is malt sugar syrup, the solution of dextrin or high in dextrin is admitted to trough 5, while the high maltose solution is run into trough 6. The rollers are then rotated, roller 2 in an anti-clockwise direction and rollers 3 and 4 in a clockwise direction. The peripheral velocity of roller 2 is preferably slightly greater than that of rollers 3 and 4, so that the film of solution carried up upon rollers 3 and 4 is drawn upon the surface of roller 2 as it passes over them. By this arrangement, a film of the solution contained in trough 5 is first applied to roller 2 and then a film of the more adhesive solution in trough 6 is applied outside of this film. The film of the more adhesive solution is thus kept out of contact with roller 2 and does not, therefore, stick to the roller when dried. The two films are scraped from the roller 2 by the knife 11 and fall into the receptacle 12 in the form of a dry powder.

In the modification of the apparatus shown in Fig. 2, rollers 3 and 4 are placed at such a distance from the roller 2 that the film of solution upon them is not brought directly in contact with the roller 2. In this modification, the rollers 3 and 4 are rotated at a sufficiently high velocity to throw the solution upon them against the roller 2 by centrifugal force.

The axles of the rollers 3 and 4 may be so supported as to be vertically adjustable. In this case these rollers may be so adjusted as to operate either as shown in Fig. 1 or as in Fig. 2.

The process may be used to dry a single highly adhesive liquid which could not be dried on a heated roller by the ordinary method. In this case the adhesive liquid is placed in the trough 6 and oil or other suitable liquid of low adhesiveness is placed in the trough 5 to form a film which shall prevent the adhesive liquid from adhering to the roller 2.

An important use of the process is to obtain a dry product which is composed of a mixture of the solid constituents of solutions of different adhesiveness. In this case, as already explained, the more ad-

hesive solution is placed in the trough 6 and is thus prevented from coming in contact with the roller. Furthermore, the process permits of the regulation of the proportions of the constituents of the different solutions which appear in the dried product. This is done by regulating the thickness of the films of the various solutions applied to the roller 2. Regulation may be accomplished in various ways. Thus, a thicker film of one solution may be produced by maintaining that solution at a higher level in its trough by admitting the solution to the trough more rapidly. A thicker film of the solution may also be applied by rotating the roller which is applying the film more rapidly. This method is peculiarly applicable when the film is applied centrifugally, as shown in Fig. 2.

It is obvious that many modifications may be made in the described means for carrying out the process without departing from our invention. Thus, the drying roller may itself dip into a trough containing one of the liquids, while the other liquid is applied by a roller similar to roller 3. Or one or both of the solutions may be applied by suitable spraying devices or by means of any other mechanism for applying films to a roller. If it is desired to obtain a mixture of the solid constituents of more than two liquids, additional rollers and troughs similar to rollers 3 and 4 and troughs 5 and 6 may be used, or a number of spraying devices or other means for applying films may be used equal to the number of liquids to be dried. Thus, any number of liquids may be dried and the solid constituents mixed in any desired proportion.

What we claim is:

1. The method of obtaining the solid constituents of an adhesive liquid in dry form, which consists in spreading a film of a less adhesive liquid over a surface, spreading a film of the adhesive liquid over this film, drying said films upon said surface, and removing them from said surface.

2. The method of obtaining the solid constituents of an adhesive liquid in dry form, which consists in spreading a film of a less adhesive liquid over a heated surface, spreading a film of the adhesive liquid over this film, drying said films upon said surface, and removing said films from said surface.

3. The method of obtaining a mixture of the solid constituents or liquids of different adhesiveness, which consists in applying a film of the less adhesive liquid to a surface, applying a film of the more adhesive liquid over said film, and scraping said films from said surface after they have dried thereon.

4. The method of obtaining a mixture of solid constituents of liquids, which consists in successively applying films of said liquids

to a surface, and scraping said superimposed films from said surface after they have dried thereon.

5. The method of obtaining a mixture of solid constituents of liquids in given proportions, which consists in successively applying films of said liquids to a surface, the thickness of the film of each liquid being proportional to the amount of the solid constituents of that liquid desired in the dry product, and scraping said superimposed films from said surface after they have dried thereon.

6. The method of obtaining a mixture of the solid constituents of liquids of different adhesiveness, which consists in successively applying films of the said liquids to a heated surface, the nethermost film being composed of one of the liquids of comparatively low adhesiveness, and removing said films from said surface after they have dried thereon.

7. The method of obtaining a mixture of solid constituents of liquids, which consists in applying a film of one of the liquids to a surface, partially drying said film, applying a film of another liquid upon said partially dried film, and scraping said superimposed films from said surface after they have dried thereon.

8. The method of obtaining a mixture of solid constituents of liquids, which consists in applying a film of one of the liquids to a surface, applying a film of another of the liquids to said first mentioned film, and scraping said superimposed films from said surface after they have dried thereon.

9. A continuous method of obtaining a mixture of solid constituents of liquids, which consists in applying a film of one of the liquids to a moving surface, applying a film of another of said liquids to said surface at a point to the rear of the point where said first mentioned film is applied,

and scraping said superimposed films from said surface after they have dried thereon.

10. The method of obtaining the solid constituents of a solution of maltose in dry form, which consists in spreading a layer of a less adhesive substance over a surface, spreading a film of the maltose solution over said layer, drying said film, and removing said film and said layer from said surface.

11. The method of obtaining the solid constituents of malt sugar syrup in dry form, which consists in spreading a film of a solution of dextrin over a surface, spreading a film of a solution of maltose over said film, drying said films upon said surface, and removing said films from said surface.

12. The method of obtaining the solid constituents of malt sugar syrup in dry form, which consists in spreading a film of the syrup in which the ratio of dextrin to maltose is greater than 45:55 over a surface, spreading a film of a syrup in which the ratio of maltose to dextrin is greater than 55:45 over said film, drying said films upon said surface, and removing said films from said surface.

13. The method of obtaining the solid constituents of an adhesive liquid in dry form, which consists in spreading a layer of a less adhesive material over a surface, spreading a film of the adhesive liquid over this layer, drying said film, and removing said film and said layer from said surface.

In testimony whereof, we have hereunto set our hands in the presence of witnesses this fourth day of March, 1915.
